UNITED STATES PATENT OFFICE.

JOHN G. FRIBERG, OF MAIDEN ROCK, WISCONSIN, ASSIGNOR OF ONE-THIRD TO GEORGE E. BRASINGTON, OF MAIDEN ROCK, WISCONSIN, AND ONE-THIRD TO OSCAR H. ANDERSON, OF PLUM CITY, WISCONSIN.

ADJUSTABLE PAIL-COVER.

1,160,061.

Specification of Letters Patent.

Patented Nov. 9, 1915.

Application filed September 17, 1914. Serial No. 862,216.

To all whom it may concern:

Be it known that I, JOHN G. FRIBERG, a citizen of the United States, residing at Maiden Rock, in the county of Pierce and

5 State of Wisconsin, have invented certain new and useful Improvements in Adjustable Pail-Covers; and I do declare the following to be a full, clear, and exact description of the invention, such as will enable others 10 skilled in the art to which it appertains to make and use the same.

This invention relates to new and useful improvements in covers for pails, kettles and the like and more particularly to an adjustable cover therefor and the primary object of the invention is to provide a device of this character which may be readily adjusted to various sizes whereby the same may be applied to pails and kettles of various sizes.

20 A further object of the invention resides in providing a member in connection with this adjustable pail cover which is designed to receive a particularly constructed additional member such as a strainer, and a still further object resides in providing an improved locking means for the cover which is designed to retain the various parts of the device in assembled position.

30 A still further object resides in providing a device which is simple and durable in construction, inexpensive to manufacture and one which will be very efficient and useful in operation.

35 With these and other objects in view the invention consists in the novel features of construction, combination and arrangement of parts hereinafter referred to and more particularly pointed out in the specification 40 and claims.

In the accompanying drawings forming a part of this application:—Figure 1 is a plan view of a device constructed in accordance with my invention; Fig. 2 is a front elevation thereof; Fig. 3 is a rear elevation of the same; Fig. 4 is a transverse section as seen on line 4—4 of Fig. 1 looking in the direction of the arrow; Fig. 5 is a bottom plan view of the device; Fig. 6 is a vertical section through a pail having a cover applied thereto constructed in accordance with my invention and disclosing in elevation a strainer applied in connection with the

cover; Fig. 7 is a detail perspective view of one of the locking members for the device; 55 and Fig. 8 is a plan view of a slightly modified form of the invention.

In describing the invention I shall refer to the drawings in which similar reference characters designate corresponding parts 60 throughout the several views and in which— 1 designates a pail or kettle of any desired shape and size to which is adapted to be applied my improved adjustable cover. This cover consists of a substantially circular 65 base plate 2 formed of two sections 3 and 4 which are pivoted as indicated at 5 to a linking strip or plate 6. The meeting edges of said sections 3 and 4 at the pivotal ends thereof are cut away as shown at 7 70 whereby to permit said sections to be swung outwardly or inwardly with respect to one another to expand the cover. These sections of the covering plate 2 are formed of thin metal and are permitted to slightly 75 overlap so that the same may be readily swung inwardly when desired. In order to limit the expansive movement of said members with respect to one another, said sections are provided at the edges thereof diametrically opposite the pivotal points with laterally extending lugs 8 which are designed to abut one another when the meeting edges of said sections register one with the other, as clearly shown in Fig. 2 of the 80 drawings.

The link or the like 6 to which the sections 3 and 4 are pivotally connected is provided with a depending lug or flange 9 while the sections 3 and 4 at points diametrically opposite one another and midway between the pivotal and free ends of the same are provided with depending lugs or flanges 10. The flanges 9 and 10 are adapted to project downwardly and engage the 95 body or upper peripheral edge of the pail when the plate 2 is applied to the latter. It will be appreciated from the construction above described and shown in the drawings that this member 2 may be applied to 100 pails or kettles of various sizes, the same being adjustable to clamp tightly around the upper edge of any receptacle to which the same is applied. In order to lock the sections of this plate 2 in any adjusted position 105 with respect to one another, each section

thereof is provided with a locking strap or link 11 which is pivoted at its one end at a point on the upper face of the section at a point substantially diametrically opposite the pivotal point of the section. The free end of each strap is provided with an upwardly bent lug 12 which forms a finger piece and the one edge of this strap or link 11 continuing from the free end thereof is 10 provided with a plurality of teeth 13. These straps or links 11 are so applied to the sections as to be permitted to overlap and interlock with one another in the various positions of the sections 3 and 4 so that in any 15 position of said sections these straps may be disposed so that the teeth thereof interlock and thus positively secure said sections in their adjusted positions. These members 11 may be readily disengaged when it is desired to adjust or remove the plate 2 from 20 its position on the receptacle.

The meeting edge of each of the sections 3 and 4 is cut away about centrally whereby to form an enlarged opening 14 in the member 2. Applied to the top face of this plate 2 is an additional plate 15 which is formed somewhat on the order of a strip being narrow at its ends and enlarged centrally as shown at 16. The enlarged central portion 25 of the strip or plate 15 has a polygonal central opening 17 therein which may be of any design but which in the drawing is shown octagonal. The edges of the walls of this opening are provided with depending 30 flanges 18. The one narrow end of this strip or plate 15 is designed to be received in frictional engagement between the faces of the sections 3 and 4 and the link-like plate 6, as clearly shown in Fig. 1 of the drawings 35 and when so disposed this strip or plate 15 will extend diametrically across the plate 2. The opening 17 in the member 15 is preferably smaller than the opening 14 in the plate 2 and will be disposed substantially within 40 the latter. The plate or strip 15 is provided on its upper face adjacent its free end with an upstanding projection 19 which is designed to form a finger piece but which also cooperates with the teeth of the members 11 45 whereby to lock this member 15 in position in the plate 2. The projection 19 also affords a means for engagement with the teeth 13 of said members 11 so that when this plate 15 is applied the teeth of the members 11 do 50 not necessarily engage one another. It is obvious, therefore, that this projection 19 performs a double function in affording a finger or lifting piece for the member 15 and also providing a means whereby the 55 straps or members 11 may be readily engaged therewith for locking the parts in their proper positions with respect to one another.

The opening 17 is of polygonal design in 60 order to receive therein a particularly de-

signed depending portion of an improved funnel 20 which is specifically described and claimed in my concurrently filed application. As shown in the drawings, this particularly 70 constructed portion of the funnel is octagonal in design but it will be understood that the same may be of any desired shape and of course the opening 17 in the member 15 will be designed to correspond therewith.

This adjustable top may of course be used 75 in other connections than that described for the purpose of supporting the funnel, in fact, it may be used as an ordinary top for the receptacle. When the funnel is not in use a covering means for the opening 17 is 80 provided. This covering means consists of a pair of semi-circular plates 21 which are pivoted as shown at 22 to the upper face of the strip or plate 15 on one side of the opening 17. When it is desired to use the funnel 85 in connection with this top, these plates are disposed to their outward or extended positions, as shown in Fig. 1 of the drawings but when said funnel is not in use these plates are disposed to their closed position as 90 shown in Fig. 5 of the drawings.

In Fig. 8 I have shown a slightly modified form of the invention wherein an adjustable pail cover is provided for use on and application to a pail or the like without the use of the strainer and its adjunctive parts. In this form of the invention a pail cover 23 is provided the same consisting of a pair of semi-circular sections 24 and 25 which are pivoted together at a point indicated as 26 to permit the straight inner edges to overlap one another. The peripheral edges of the sections 24 and 25 are provided at predetermined points thereon with integral depending lugs 27 which are similar to the lugs 9 and 10 in the first mentioned form for the purpose of gripping the sides of the pail or kettle to which the device is applied. The edges of the members 24 and 25 at points diametrically opposite the pivotal point 26 are provided with the depending lugs or the like 28 similar to the lugs 8 in the first mentioned form, which lugs limit the expansive movement of the sections 24 and 25 with respect to one another as will 105 appear obvious. This form of the invention differs from the first mentioned form in that no central opening is provided in the cover so that same may be used in connection with any kettle, pail or the like for the same purpose as the ordinary pail cover. In view of the adjustability of this cover, however, the same may be applied to use in connection with pails or receptacles of various sizes. In 110 order to lock the sections of the cover in the positions to which the same are adjusted, a pair of pivotal locking arms are provided, one being carried on each section as are the arms 11 of the first mentioned form. The free ends of these locking arms overlap one 115

another and are provided with locking teeth for engagement with one another the same as the locking arms 11 heretofore described.

From the foregoing description of the construction of my improved device the manner of applying the same to use and the operation thereof will be readily understood and it will be seen that I have provided a simple, inexpensive and efficient means for carrying out the objects of my invention.

While I have particularly described the elements best adapted to perform the functions set forth, it is obvious that various changes in form, proportion and in the minor details of construction may be resorted to, within the scope of the appended claims, without departing from the spirit or sacrificing any of the principles of the invention.

Having thus described my invention, what I claim is:

1. A device of the class described comprising a pair of plate sections movable toward and from each other and adapted to overlap, the meeting edges of said sections being cut away centrally to provide a central opening therebetween, and a member applied to the upper face of said sections having a central aperture therein to align with the aforesaid opening.

2. A device of the class described comprising a pair of pivoted plate sections adapted to overlap one another, means for limiting the expansive movement of said sections with respect to one another, depending lugs formed on said sections to provide gripping members thereon, the meeting edges of said sections being cut away centrally to provide a central opening therebetween, a member applied to the upper face of said sections and also having a central opening therein alining with the aforesaid opening, means for locking the plate sections in various adjusted positions and simultaneously locking said member in position thereon.

3. A device of the class described comprising a pair of plate like sections pivoted together and having their meeting edges cut away centrally to provide an opening therebetween, a member applied to the upper face of said sections also having a central opening therein alining with the aforesaid opening, covering means for said openings and locking strips carried on the sections adapted for engagement with one another to secure said sections in various adjusted positions.

4. In a device of the class described, a pair of plate sections, a strip pivotally connecting the same together to permit portions of said sections to overlap one another, the meeting edges at the central portions of said sections being cut away to provide an opening therebetween, means for limiting the expansive movement of said sections with respect to one another, an additional plate held frictionally at its one end between said plate sections and the aforesaid strip to extend diametrically across said plate sections, said additional plate having a central opening therein alining with the aforesaid opening, and means for locking said plate sections in various positions and simultaneously securing the additional plate in position thereon.

5. A device of the class described comprising a pair of plate like sections pivoted together and having their meeting edges cut away centrally to provide an opening therebetween, an additional plate member applied to the upper face of said sections also having a central opening therein alining with the aforesaid opening, an upstanding projection on one end of the additional plate member, a pair of locking strips pivotally carried on the plate sections and adapted for engagement with said projection to lock said plate sections in various adjusted positions and simultaneously secure the plate member thereon, and a covering means for said openings.

6. An adjustable cover for receptacles comprising a pair of semi-circular plate-like sections pivoted together in overlapping relation immediately adjacent the peripheral edges thereof, gripping lugs carried on said sections for engagement with a receptacle, additional lugs formed on said plate sections at points thereon diametrically the point of pivotal connection between the sections, said lugs being adapted for engagement with one another to limit the expansive movement of said sections, and a pair of strips pivotally carried on the locking sections and adapted for engagement to lock the sections in various adjusted positions with respect to one another.

In testimony whereof I have hereunto set my hand in presence of two subscribing witnesses.

JOHN G. FRIBERG.
